UNITED STATES PATENT OFFICE.

GUSTAV A. BRACHHAUSEN, OF RAHWAY, NEW JERSEY.

MECHANICAL MUSICAL INSTRUMENT.

SPECIFICATION forming part of Letters Patent No. 657,081, dated September 4, 1900.

Application filed April 4, 1900. Serial No. 11,417. (No model.)

To all whom it may concern:

Be it known that I, GUSTAV A. BRACHHAUSEN, a resident of Rahway, Union county, State of New Jersey, have invented certain new and useful Improvements in Mechanical Musical Instruments, of which the following is a specification.

My invention relates to mechanical musical instruments, and while the invention is particularly adapted for that character of instruments wherein separate note sheets or disks are automatically conveyed to and from operative position in the instrument the invention may be applied to any musical instrument in which its application is available.

Heretofore in the manufacture of automatic musical instruments wherein a single spring-drum has been employed it has been customary to constantly rotate the driving-wheel of the instrument during the movement of the motor or spring-drum. This resulted in the note sheets or disks being stopped and started at different intervals—that is to say, there was a liability of the note-disk being deflected and brought into engagement with the rotating driving-wheel before the disk was properly clamped in operative position and was ready to play the instrument, and the result would be that a partial rotation would be imparted to the disk before the playing was started, and as a consequence the tune would not start at the beginning thereof, nor would the instrument stop playing at the end of the tune. This defect would continue at each automatic operation of the device until the sheet or disk was properly positioned by hand in the carriage.

The object of my present invention is to overcome this and other defects existing in the prior structures; and to this end my invention consists in the novel arrangement and combination of the parts to be hereinafter described and claimed.

In the accompanying drawings, wherein like characters represent corresponding parts in the various views, Figure 1 is a vertical sectional view of the upper portion of a musical instrument embodying my invention, the section being taken on line 1 1 of Fig. 3 and looking in the direction of the arrow. Fig. 2 is a fragmentary detail plan view of the

spring-drum. Fig. 3 is a horizontal sectional view of the instrument, the section being taken on lines 3 3 of Fig. 1. Fig. 4 is an enlarged detail fragmentary sectional view of a portion of the device, the section being taken on lines 4 4 of Fig. 5. Fig. 5 is a horizontal sectional view of the same, the section being taken on lines 5 5 of Fig. 4. Fig. 6 is a detail vertical sectional view of a modified form of device embodying my invention, a sufficient number of parts being shown to illustrate my invention. The section is taken on lines 6 6 of Fig. 7 and is looking in the direction of the arrow on the said section-line. Fig. 7 is a fragmentary front elevation of the same.

Referring specifically to Figs. 1 to 5, inclusive, of the drawings, 1 indicates the framing of the instrument in which the various working parts of the device are illustrated. Contained within this casing is a note-sheet carriage 2, which may be of the usual or any preferred construction. Motion is communicated to this carriage in any suitable manner to bring the note disks or sheets 3 carried thereby into a position to be transported to and from operative position in the instrument. In the present instance I have illustrated a rock-shaft 4, which is pivoted at its upper end in a casting 5 and is provided with an arm 6, that carries an antifriction-roller 7, that is adapted to project into an internal cam-groove carried upon a cam-piece 8. The lower end of the rock-shaft 4 is suitably connected to the carriage, so as to impart motion thereto when the rock-shaft is moved by means of the cam 8. Motion is transmitted to the cam 8 by a wheel 9, that is rigidly connected thereto, and a pawl 10 co-operates with the wheel to impart an intermittent rotary motion thereto. This pawl 10 is carried by an arm 11, fixed upon a rock-shaft 12, which has motion imparted thereto by the spring-drum 13. The rock-shaft 12 has a second arm 14 rigidly connected thereto, and the free end of this arm bears against and co-operates with a locking-pawl 15. This locking-pawl is made in the form of a two-arm lever, the nose 16 of which is adapted to contact with a tooth on the wheel 9 and prevent a movement thereof in the direction of the arrow in Fig. 1. The other arm of this locking-pawl is adapted to be acted upon by the free end

of the arm 14, so as to elevate the nose 16 of the pawl, and thus permit a full rotation of the wheel 9 in the direction of the arrow. A second locking-pawl 17 is pivoted to a fixed portion of the instrument, as indicated at 18, and is normally maintained in engagement by a spring 19. This pawl 17 projects in an opposite direction to that of the pawl 16, so as to prevent a backward movement being imparted to the stepping wheel 9. It will be observed that by this construction an oscillation of the rock-shaft 12 will simultaneously move the locking-pawl 16 out of engagement with the tooth of the stepping wheel 9 and will transmit an intermittent rotary movement to said stepping wheel through the stepping pawl 10, so as to move the note-sheet carriage 2. It will be understood that the cam 8 is a continuous one, so that the carriage 2 may be reciprocated in opposite directions to bring each of the note sheets or disks in the carriage into the path of the transporting mechanism, by means of which any one of the sheets may be conveyed to and from operative position in the instrument.

The note-disk raising or conveying mechanism consists in the present instance in arms 20, which are bifurcated at the outer ends, as indicated at 21 in Fig. 3 of the drawings. These arms are connected to flexible bands 22, (see Fig. 1,) each of which has its opposite end connected to a band-pulley 23, which band-pulleys are mounted upon a shaft 24. This shaft 24 is likewise provided with a band-pulley 25, which has connected thereto one end of a flexible band 26, that is conveyed over a guide-pulley 27 and has its opposite end connected to a lever 28, as indicated at 29. This lever 28 is pivoted, as indicated at 30, to a fixed bracket 31 and has an extension or second arm 32, that is provided with an antifriction-roller 33 at its free end. This antifriction-roller is adapted to bear upon a cam-track 34 on the drum 13, and an oscillating movement is thus transmitted to the arm 28 and to the band-pulleys 25 and 23, and the arms 20 are conveyed up and down in accordance with the positioning of the antifriction-roller 33 upon its cam-track, and the note-disks are thus elevated from the carriage into the operative position in the instrument and are again deposited in the carriage after the instrument has been played.

Upon the shaft 24 is carried a guide-arm 35, which has an antifriction-roller 36 mounted in the free end thereof. It will be observed that when the shaft 24 is moved in the manner hereinbefore described the arm 35 will be oscillated into and out of the path of the note-disk during its movement to and from operative position in the instrument. The action of this arm is as follows: As the note-disk is elevated into the operative position the arm 35 is simultaneously moved into contact therewith, so as to give a slight lateral deflection to the sheet or disk to prevent the same from reaching contact with the star-wheels, which

vibrate the teeth of the combs 37, so that no premature playing of the instrument can take place. During the return of the note-disk to the carriage this arm is again operated with the shaft 24, so as to maintain the sheet out of contact with the star-wheels until the sheet has reached the point where there is no longer danger of such contact taking place, when the arm will pass to a position where it is out of the path of the movement of the note-disk.

The spring-drum 13 hereinbefore referred to may be wound in any suitable manner. In the present instance a winding-post 38, which is adapted to receive the usual winding-crank and is provided with a pinion 39, that meshes with the internal gear 40, is employed. The periphery of this internal gear 40 is formed as a ratchet-wheel 41, with which a pawl 42 cooperates to prevent a backward movement thereof. The wheel 40 is suitably connected to the inner end of the spring in the spring-drum 13. The drum 13 is provided with a mutilated gear 43, the cut-away portions of which are represented at 44. This gear cooperates with a pinion 45, rigidly connected to the note-disk-driving wheel 46, which is pivoted to a fixed portion of the instrument. The driving-wheel 46 is provided with an arm or laterally-projecting flange 47, which has an indenture or locking-recess 48 in the inner face thereof. Cooperating with this locking-recess 48 is a latch or locking-abutment 49, which in the present construction is pivoted at 50 to a pin 51, carried by a bed-plate 52. This locking latch or abutment is normally maintained in full-line position (represented in Fig. 5 of the drawings) by a spring 53. The locking-abutment is likewise provided with a nose 54, with which the clamping-rod 55 is adapted to contact in its movement from the full-line to the dotted-line position. (Represented in Fig. 5 of the drawings.) It will be observed that when the parts are in full-line position the locking abutment or latch 49 is in the locking-recess 48 of the driving-wheel and locks the same against rotation, whereas when it has been moved to the dotted-line position by the clamping-rod the driving-wheel is free to be rotated. It will of course be understood that the clamping-rod 55 is moved in the usual or any preferred manner automatically to clamp the note-disk in the operative position.

In the present instance the clamping-rod 55 is provided with antifriction-rollers 56, and each end of said rod is connected to a rod 56^X, which projects toward the rear of the machine, where it is operatively connected to the rock-shaft 57. The clamping-rod 55 is normally maintained in the releasing position (illustrated in Fig. 3 and in full lines in Fig. 5) by the springs 58, surrounding the rods 56^X and tending to force the clamping-rod in the direction of the arrow in Figs. 3 and 5 of the drawings. When, however, a note-disk has been elevated into the operative position by the transporting

mechanism, the clamping-rod will be automatically operated to clamp the note-disk in operative position.

The plain and toothed portions of the mutilated gear 43 are so arranged with relation to each other that the plain portion of the mutilated gear will have reached the pinion 45 when the note-disk is being conveyed to and from the operative position in the instrument 5 and when the clamping-rod is in releasing position, and this plain portion will extend until such time as the clamping-rod is moved to the dotted-line position in Fig. 5 to clamp a note-disk in the operative position, when motion will be immediately transmitted to the driving-wheel by the geared portion of the mutilated gear 43. It will be observed that the driving-wheel 46 will be stopped and started at the same point at every intermittent 10 movement thereof by reason of the fact that as soon as the clamping-rod 55 starts to release the disk the latch or locking-abutment 49 will bear upon the internal face of the rim 47 of the driving-wheel, and when the locking-notch 48 thereof arrives at a point opposite the latch it will by its spring-pressure be forced into the locking-recess to retain the driving-wheel against rotation. An examination of Fig. 4 of the drawings will indicate that 15 this locking takes place immediately after the pinion is out of mesh with the geared portion of the mutilated gear 43. On the other hand, as soon as the clamping-rod is moved into operative position the locking-latch will be automatically moved with it to the unlocking 20 position (represented in dotted lines in Fig. 5,) and when the driving-wheel has been released in this manner the geared portion of the mutilated gear 43 will immediately come into 25 mesh with the pinion to rotate the driving-wheel, and thus transmit motion to the note-disk 3.

In Figs. 6 and 7 of the drawings I have shown a somewhat different arrangement for 45 accomplishing the same end. In these figures 60 designates the spring-drum, which is provided with a mutilated gear 61. Coöperating with the gear 61 is the pinion 62, which is connected to rotate with the note-disk 40 driving wheel 63. The driving-wheel 63, together with its pinion, is loosely mounted on a pivot 64, carried by a lever 65, which is pivoted at 66. This lever extends beyond its pivot, and the extended portion is pivotally 50 connected, as indicated at 67, to a link 68. The opposite end of this link 68 is pivotally connected, as indicated at 69, to a depending arm or bracket 70, which is connected to one of the rods 71, which transmits motion to the 55 clamp-rod 72. The inner end of each of the arms 71 is provided with an abutment 73, with which a wiper-arm 74 coöperates to move the clamping-rod 72 against the tension of its springs 75, it being understood that the arms 60 65 74 are connected to a rock-shaft 76, which is moved in any suitable manner from the drum

transmitted to the clamping-rod will by these means be communicated to move the driving-wheel and its pinion bodily around their 70 pivot 66. The driving-wheel 63 is provided with a laterally-extending flange 77 in somewhat the same manner as shown in Fig. 5 of the drawings. This flange is likewise provided with a locking-recess 78, which is adapted to receive a fixed pin or locking projection 75 79. This pin is rigidly carried upon the bed-plate 80 or some other fixed portion of the instrument, and as the driving-wheel is moved bodily around the pivot 66 it will cause an 80 engagement or disengagement of the locking pin and recess in accordance with the direction in which the driving-wheel is moved. The blank portion 81 of the mutilated gear is so placed with relation to the movement of 85 the parts that it will reach the pinion 62 when a movement of a note-disk to and from operative position in the instrument is taking place and when the clamping-rod 72 is in the releasing position, as indicated in the drawings. It will be observed that at this time 90 the locking-pin is seated in the locking-recess 77 and no rotary movement of the driving-wheel can take place. When, however, the rock-shaft 76 is vibrated to move the arm 95 74 in the direction of the arrow γ in Fig. 6, the rods 71 will receive a corresponding movement to move the clamping-rod 72 in order to clamp the note-disk in operative position. This same movement will cause a corresponding 100 movement to be transmitted to the link 68, and will thus force the driving-gear in the direction of the arrow α . This movement imparted to the driving-wheel will cause the projections 82 thereof to be projected into 105 the coöperating apertures in the note-disk and will simultaneously release the driving-wheel from the fixed locking-pin 79. As soon as this movement has taken place the drum 110 will have completed its movement through the plain portion of the mutilated gear and will have brought the tooth portion thereof into engagement with the pinion 62, when a rotary motion will be transmitted to the driving-wheel to effect a playing of the instrument. 115

It will be observed that by my invention the driving-wheel will be automatically locked and maintained against rotation during the movement of the disks to and from operative position and until the note-disk is properly clamped in place and is ready to play the instrument, when the driving-wheel will be automatically unlocked and rotated to transmit a playing movement to the note 120 sheet or disk. It will likewise be seen that by the construction herein shown and described no movement can possibly be transmitted to the note sheet or disk by the driving-wheel 125 until the sheet or disk is properly secured in playing position. 130

While I have described with considerable detail two forms of the device embodying my invention, I would have it understood that

various changes in detail and arrangement may be made without departing from the spirit of my invention and in order to adapt the invention to various forms of mechanical musical instruments.

Having described my invention, what I claim, and desire to secure by Letters Patent, is—

1. In a mechanical musical instrument the combination of a note-sheet-driving wheel adapted to engage and transmit motion to a note-sheet, means for transmitting motion to said driving-wheel and means adapted to enter into locking engagement with the driving-wheel and to lock it against movement.
2. In a mechanical musical instrument the combination of a note-sheet-driving wheel, automatic means for intermittently transmitting motion thereto and means for automatically and intermittently entering into locking engagement with the driving-wheel to lock said driving-wheel against movement.
3. In a mechanical musical instrument the combination of a spring-motor, a note-sheet-driving wheel, automatic means operable from said motor for intermittently transmitting motion to the driving-wheel and means for automatically and intermittently locking said driving-wheel against movement, said locking means being controlled by the motor.
4. In a mechanical musical instrument the combination of a note-sheet-driving wheel, means for operating said driving wheel, means for conveying separate note-sheets to and from operative position in the instrument, mechanism for clamping a note-sheet in operative position and means coöperating with the clamping mechanism for locking the driving-wheel out of action.
5. In a mechanical musical instrument the combination of a note-sheet-driving wheel, means for automatically and intermittently operating said driving-wheel, means for automatically conveying separate note-sheets to and from operative position in the instrument, mechanism for automatically clamping a note-sheet in operative position and means controlled by the clamping mechanism for locking the driving-wheel out of action.
6. In a mechanical musical instrument the combination of a note-sheet-driving wheel, means for operating said driving-wheel, means for conveying separate note-sheets to and from operative position in the instrument, mechanism for clamping a note-sheet in operative position and a locking-abutment carried by a fixed portion of the instrument, which locking-abutment is in engagement with the driving-wheel to maintain the same against movement when the clamping mechanism is ineffective to maintain a note-sheet in operative position.
7. In a mechanical musical instrument the combination of a note-sheet-driving wheel, means for automatically and intermittently operating said driving-wheel, means for automatically conveying separate note-sheets to

and from operative position in the instrument, mechanism for automatically clamping a note-sheet in operative position, a locking-abutment carried by a fixed portion of the instrument which locking-abutment is in engagement with the driving-wheel to maintain the same against movement when the clamping mechanism is ineffective to maintain the note-sheet in operative position and is out of engagement therewith when the clamping mechanism is effective to maintain the note-sheet in operative position and automatically-operated means controlled by the clamp mechanism for effecting the locking and release of the driving-wheel.

8. In a mechanical musical instrument the combination of a note-sheet-driving wheel adapted to engage and transmit motion to a note-sheet, said driving-wheel having a locking-recess therein, a locking-abutment adapted to be received in said recess and to be withdrawn therefrom and means for automatically bringing the locking-abutment and locking-recess into engagement to lock the driving-wheel against rotation.

9. In a mechanical musical instrument the combination of a note-sheet-driving wheel, a pinion for said driving-wheel and a mutilated driving-gear adapted to mesh with said pinion to transmit intermittent motion to the driving-wheel.

10. In a mechanical musical instrument the combination of a note-sheet-driving wheel, a pinion for said driving-wheel, a mutilated driving-gear adapted to mesh with said pinion and to transmit motion to the driving-wheel and means for locking the driving-wheel against rotation when the pinion thereof is out of mesh with the driving-wheel and for unlocking the driving-wheel when the pinion thereof is in mesh with the driving-wheel.

11. In a mechanical musical instrument the combination of means for conveying separate note-sheets to and from operative position in the instrument, means for clamping a note-sheet in operative position, a note-sheet-driving wheel, a pinion for said driving-wheel and a mutilated driving-gear adapted to mesh with said pinion to transmit motion to the driving-wheel when the clamping mechanism is effective to maintain the note-sheet in operative position and to be out of mesh with said pinion when the clamping mechanism is ineffective to clamp a note-sheet in operative position.

12. In a mechanical musical instrument the combination of means for conveying separate note-sheets to and from operative position in the instrument, means for clamping a note-sheet in operative position, a note-sheet-driving wheel, a pinion for said driving-wheel, a mutilated driving-gear adapted to mesh with said pinion to transmit motion to the driving-wheel when the clamping mechanism is effective to maintain a note-sheet in operative position and to be out of mesh with said pinion when the clamping mechanism is ineffective

to clamp a note-sheet in the operative position and means for locking the driving-wheel against rotation when the pinion thereof is out of mesh with the driving-wheel.

- 5 13. In a mechanical musical instrument the combination of means for conveying separate note-sheets to and from operative position, means for clamping a note-sheet in operative position, a note-sheet-driving wheel having a locking-recess therein, a pinion for said driving-wheel, a mutilated driving-gear adapted to mesh with said pinion to transmit an intermittent motion to the driving-wheel and a pivoted locking latch or abutment adapted
- 10 to engage in recess of the driving-wheel and to be controlled in its movement by the clamping mechanism.

14. In a mechanical musical instrument the combination of means for conveying separate note-sheets to and from operative position in the instrument and a guiding-arm connected to rotate with a part of the conveying means in a path traversing the path of the note-sheets so as to contact with and deflect the note-sheets laterally in their movement to the operative position in the instrument and to be withdrawn from contact with the sheets in their movement from the operative position.
